UNITED STATES PATENT OFFICE.

ROBERT S. RILEY, OF WORCESTER, MASSACHUSETTS, ASSIGNOR TO SANFORD RILEY STOKER CO., LTD., OF WORCESTER, MASSACHUSETTS, A CORPORATION OF MASSACHUSETTS.

AIR-ADMITTING DEVICE FOR UNDERFEED RETORTS.

1,283,425.

Specification of Letters Patent.

Patented Oct. 29, 1918.

Application filed August 27, 1915. Serial No. 47,694.

To all whom it may concern:

Be it known that I, ROBERT SANFORD RILEY, a citizen of the United States, residing at Worcester, in the county of Worcester 5 and State of Massachusetts, have invented a new and useful Air-Admitting Device for Underfeed Retorts, of which the following is a specification.

This invention relates to the type of underfeed stokers represented in my prior Patent No. 1,090,651, granted March 17, 1914. This is the type of underfeed stokers in which the fuel is fed from below through the retort longitudinally.

The principal objects of this invention are to provide means for overcoming the difficulty which has sometimes been experienced in this type of stoker, due to the fact that when the air is supplied only at the edges 20 of a retort, there is a tendency for the fire to concentrate along the lines adjacent the retorts; to provide a more even distribution of the air throughout the fuel all along the retort and clear across the same, thus assuring more perfect distribution thereof, and also to dispense with the necessity of the lateral openings around the sides of the retort as heretofore used.

Reference is to be had to the accompanying drawings which show two retorts and in which,

Figure 1 is a longitudinal section of a portion of a stoker constructed in accordance with this invention;

Fig. 2 is a plan of the same part of the stoker with parts in section; and

Fig. 3 is a sectional perspective view on the line 3—3 of Fig. 2.

The invention is shown as applied to a stoker in which a number of retorts are located side by side each comprising reciprocable sides 11 supporting the grates and also having side plates 12 passing through the front wall and extending inwardly therefrom under a top plate 13 in the front wall and over a bottom plate 14 coextensive with the side plates. Through the openings thus formed the fuel is introduced by any desired means, such for example as shown in my above mentioned patent.

Instead of the air conducting means shown in said patent, which conducts the air into the fuel from the upper part of the sides 11 of the fuel conducting passage

constituting the retort, air is introduced from below by the following mechanism. It will be understood, of course, that the space below the retort is connected with a blower not shown which is connected by a suitable supply conduit 21 with the space under the retorts. When forced draft is used, the air is forced through this space by the blower up into a series of conduits 23 each of which consists of a hollow wedge or keel and extends longitudinally along the center of a retort. These conduits are shown in the form of castings, each having a series of integral bars 24 across the same. They are secured in position by means of hooks 25 hooking over the bars 24 and secured by cross plates 26 on the bottom of the bottom plate 14. In this way the conduit is capable of being instantly applied and secured firmly in position and yet can be taken out for repairs or replacement with very little difficulty.

The conduit is provided in its upper half with perforations 27 extending through the inclined part of the walls thereof and the bottom plate is provided with openings 28 through which the air is adapted to pass from the space below into each conduit. It will be understood that this conduit extends longitudinally along the retort and is centrally arranged therein, but that it is wedge-shaped in order to accommodate the slope of the burning fuel at the top of the retort. For this reason the openings 27 at the lower or rear end of the conduit extend through the walls of the same from the bottom to the top but at the upper end they are located only at the top. In this way the air is introduced into the fuel just under the surface which is exposed and issues laterally so as to extend toward both side walls of the retort which are closed and do not admit air to the fuel. In this way the air is distributed across the retort and insures perfect distribution through all the fuel therein. With this construction, a fire cannot concentrate along the lines between adjacent retorts. Furthermore, on account of the shape of the conduit, it does not materially interfere with the forcing of the fuel along the retort, although it extends up into it nearly to the surface of the fuel.

Although I have illustrated and described a forced draft furnace, it will be understood

that this invention is capable of use with a furnace under natural or induced draft, the course of the air through the conduit and retort being the same as described.

Although I have illustrated and described only a single embodiment of the invention, I am aware of the fact that it can be carried out with modifications in details of construction without departing from the scope of the invention as expressed in the claims. Therefore, I do not wish to be limited in this respect, but what I do claim is:—

1. In an underfeed stoker, the combination with the movable closed sides of a retort between which the fuel is adapted to be fed longitudinally and out the end thereof, of means located in the center of the retort centrally in alignment with the course of the fuel and extending up from the bottom thereof substantially to the tops of said sides for introducing air into the center of the retort substantially throughout the length thereof and at a plurality of elevations and discharging it laterally across the retort from the center and through substantially the entire body of fuel therein.
2. In an underfeed stoker, the combination of a retort having sides providing between them a longitudinal passage for fuel

and grates supported on said sides, with a hollow conduit extending up into said passage from its bottom so as to divide the entire body of fuel in the passage into two separate streams and having openings in its opposite sides near the top thereof but below the normal level of the grates for discharging air into the fuel in the retort, and means for conducting air into said conduit from below the retort.

3. In an underfeed stoker, the combination with a retort along which the fuel is fed longitudinally, of a centrally disposed wedge-shaped air conduit located longitudinally therein and having a slanting upper edge extending downwardly from its front end to the bottom of the rear end of the retort and provided with upwardly converging side walls at the top perforated to the floor level of the retort at the rear end thereof to admit air into the center of the body of fuel in the retort.

In testimony whereof I have hereunto set my hand, in the presence of two subscribing witnesses.

ROBERT S. RILEY.
